UNITED STATES PATENT OFFICE.

VOJTECH PUC, OF PRAGUE-VINOHRADY, BOHEMIA.

SAFETY PIN.

1,415,476.

Specification of Letters Patent.

Patented May 9, 1922.

Application filed August 11, 1919. Serial No. 316,571.

(GRANTED UNDER THE PROVISIONS OF THE ACT OF MARCH 3, 1921, 41 STAT. L., 1313.)

To all whom it may concern:

Be it known that I, VOJTECH Puc, a citizen of the Czechoslovak Republic, residing at Prague-Vinoohrady, in Bohemia, have invented certain new and useful Improvements in Safety Pins, (for which I have filed applications in Austria, filed Oct. 4, 1916, patented Dec. 30, 1918, No. 77,371; in Germany, filed Oct. 7, 1916, patented June 10, 15, 1917, No. 298,314; in Spain, filed Oct. 4, 1916, patented Mar. 15, 1920, No. 71,544; in Denmark, filed Oct. 4, 1916, patented Nov. 26, 1919, No. 26,530; in France, filed Dec. 15, 1919, patented June 21, 1920, No. 15 507,413,) of which the following is a specification.

The object of this invention is to construct a safety pin which may be more easily opened and closed than heretofore without hindrance by obstructing edges of the guard.

My improvements are illustrated in the accompanying drawings, in which—

Figure 1 shows a side elevation of a safety pin embodying my improvements.

Figure 2 shows a section on the line 2—2 of Fig. 1.

Figure 3 is a view on enlarged scale and in perspective of the guard and portions of the pin connected therewith.

The stationary or fixed member A of the pin is connected with the guard B in any suitable way, and the pointed member C is of usual construction. The members A and C are connected by a coil spring at D. The

35 parts A, B and C may be of any usual construction.

The guard B is, however, of novel construction. In general outline it is similar to those usually employed. It is formed 40 with a recess having a wide inner portion c and a narrow outer portion c' which extends into the edge of the guard. When the pointed portion of the pin is housed in the guard it lies beneath a flange d of the guard.

45 When it is desired to open the pin the pointed portion is pressed inward until it comes below the recess c, c' when it may be moved outwardly therefrom. As thus far described the guard is of well known form.

50 It is, however, formed with another flange d' which, as shown, is curved at its inner edge and lies in the same plane as the flange d.

The lower side of the guard is formed 55 with a doubly inclined ridge E which is lo-

cated directly below the recess c, c'. The inner edge of the flange d' connects with the ridge as indicated at e, the top of the flange being below the upper edge of the ridge, as shown in Fig. 2. The inclined side g of the ridge is below the recess or slot c, c' and this side forms a guide for the pointed member of the pin.

By reference to Fig. 2 it will be observed that the pointed member C is securely housed when the pin is closed but when it is desired to open the pin the pointed member is merely moved inwards in the usual way and it will then ride up the inclined side g and pass out of the guard in the manner indicated by dotted lines. When the pin is being closed the pointed end is inserted in the slot c, c' and when pressed downwards will be guided by the inclination g into its housing in the guard.

A safety pin made in this way is of simple construction and may be opened and closed with great facility.

I claim as my invention:—

1. A safety pin, comprising a stationary member, a pointed member, and a guard to which the stationary member is attached, which guard is formed on one side with a slot and on the opposite side with a fixed ridge beneath the slot and the outer end of which is disposed on that side of the slot next the fixed member, said ridge having an inclined surface extending to the outer side of the guard for guiding the pointed end of the pin.

2. A safety pin, comprising a stationary member, a pointed member, and a guard to which the stationary member is attached and which is formed on one side with a slot and on the other side with a fixed ridge beneath the slot having an inclined surface extending to the outer side of the guard for guiding the pointed end of the pin.

3. A safety pin, comprising a stationary member, a pointed member, and a guard having on one side a fixed ridge formed with an inclined surface and on the opposite side with a slot above the ridge and having a fixed or stationary flange on one side which joins the ridge and is disposed below the top thereof.

In testimony whereof, I have hereunto subscribed my name.

VOJTECH PUC.
